FIG. 1.

FIG. 2.

FIG. 3.

FIG. 4.

FIG. 1 is a front prospective view of a portable building embodying my design, this view showing a side of the building, and the front of the building with the door of the building open;

FIG. 2 is a front prospective view similar to FIG. 1 with the door of the building closed;

FIG. 3 is a side elevational view of this building; and

FIG. 4 is a top plan view of this building.

The bottom of the portable building embodying my design shown in the drawings is substantially plain and unornamental.

The interior walls of the portable building embodying my design correspond in appearance to the external walls of the building, and are of complementary shape.

The broken lines designating functional parts in FIG. 1 are disclosed for illustrative purposes only.

I claim:

The ornamental design for a portable building, substantially as shown and described.
